UNITED STATES PATENT OFFICE.

MANUEL JOSÉ CUADROS, OF LIMA, PERU.

APPARATUS FOR FIRING ORDNANCE ON SHIPS.

SPECIFICATION forming part of Letters Patent No. 626,002, dated May 30, 1899.
Application filed April 19, 1898. Serial No. 678,151. (No model.)

To all whom it may concern:

Be it known that I, MANUEL JOSÉ CUADROS, a citizen of Peru, residing at Lima, Peru, have invented certain new and useful Improvements in Apparatus for Automatically Regulating the Firing of Ordnance on Ships; and I do hereby declare the following to be a full, clear, and exact description of the invention, such as will enable others skilled in the art to which it appertains to make and use the same.

This invention has relation to improvements in apparatus for automatically regulating the firing of ordnance on ships, and more particularly relates to a construction designed as an improvement on the form of these devices shown in United States Patent No. 455,176, granted to me June 30, 1891.

The object of the present invention is to provide a simple and efficient means whereby a suitably-mounted pendulum may be held in proper relation to a contact-pin for engagement therewith in order that an electrical circuit may be closed when the ship is in its normal position, so that correct firing of the guns may be had; and, furthermore, the invention contemplates the provision of means designed for retaining the contact-pin in a fixed position, so that the same may be engaged by the pendulum without the necessity of previously positioning the contact-pin.

With these and other objects in view, which will appear as the nature of the improvement is better understood, the invention consists substantially in the novel construction, combination, and arrangement of parts, as will be hereinafter fully described, illustrated in the accompanying drawings, and pointed out in the appended claims.

In the drawings, Figure 1 is a side elevation of an apparatus for automatically regulating the firing of ordnance constructed in accordance with the present invention. Fig. 2 is an enlarged detail transverse sectional view of the pendulum, the retaining-guide, and the contact-pin. Fig. 3 is a top plan view of the retaining-guide. Fig. 4 is a vertical sectional view of the contact-pin. Fig. 5 is a transverse sectional view of a vessel having the herein-described apparatus applied thereto.

Referring to the drawings, the numeral 1

designates a suitable frame which is arranged directly over the keel of a vessel and in which is disposed a suitable pendulum 2, the latter being of any approved construction and connected to the upper portion of the frame 1 by means of a universal or gimbal joint 3.

Secured within the frame 1, at the lower end thereof and directly beneath the pendulum 2, is a supporting-frame 4, and arranged upon the standards 5 of said frame is an elliptical retaining-guide 6. A depending stem 7 is removably secured within the lower portion of the pendulum 2, which stem projects into and is confined within the retaining-guide 6, a layer 8 of insulating material encircling the stem 7 to insulate the same from the guide 6. The lower end of the depending stem 7 is provided with a removable contact-point holder 9, which is provided with a transverse aperture or passage-way 9', designed for the reception of a suitable instrument whereby the contact-point holder may be secured to or removed from the stem 7, and said holder 9 is provided with a contact-point 10, designed for the purpose to be presently stated.

Extending between the standards 5 of the frame 4 is a pair of horizontally-disposed guides 11, which guides are provided with aligned openings 12, and disposed within said openings is a vertically-movable contact-pin 13, said pin being provided at its upper end with a contact-point holder 14, secured within said pin by means of a screw 15 or its equivalent. A contact-point 16 is carried by the holder 14, and it will be noted that the body of said contact-point is elongated in contradistinction to the contact-point 10, which is carried by the holder 9. The purpose of this construction is to provide a comparatively large engaging surface extending across the path of the pendulum, with which the contact-point 10 is adapted to engage for closing a circuit, and it will thus be seen that when said point 10 is brought into proper relation with the pin 13 a positive contact is made. The pendulum 2 is in electrical connection with one pole of a battery or generator, while the contact-pin 13 is similarly connected with the other pole thereof, this circuit being provided with a suitable switch, (not shown,) which is under the control of the gunner, and by reason of this when said

switch is properly manipulated the circuit may be closed simply by contact between the two points 10 and 16, which contact causes the firing of the gun.

5 The body of the pin 13 is provided with a transverse slot 17, and the standards 5 of the frame 4 are also provided with similar slots 18, a lever 19 passing through the slots 17 and 18 and being fulcrumed to one of the standards 5, as at 20. A spring 21 is secured to the lever 19, the free end of said spring 21 passing through the slot 17 and contacting with the upper end thereof, and by reason of this construction it will be seen that the contact-pin 13 is capable of a vertical yielding movement when the pendulum engages therewith, but not sufficient to prevent the points 10 and 16 making proper contact. The lever 19 is provided with an armature 22, which 10 armature is arranged adjacent to a series of electromagnets 23, and said magnets are in circuit with a suitable source of energy, which circuit also includes a switch (not shown) under the control of an officer of the vessel.

25 It will thus be seen that when the circuit embracing the magnets 23 is closed the lever 19 will be attracted toward the same with a resultant upward movement of the contact-pin 13, and said pin will be held in this position until said circuit is broken. However, 30 if it is desired to retain the pin 13 fixed in this elevated position irrespective of the magnets 23 the same may be accomplished by means of a wedge 24, the latter being carried 35 by the lever 19 at the end thereof opposite to the armature 22, said wedge being disposed within a weight 25, which weight is designed to lower the contact-pin 13 when the circuit through the electromagnets 23 is broken and 40 which is adjustably mounted upon said lever 19 by means of a screw 26 or its equivalent. The wedge 24 is adapted to enter a correspondingly-shaped notch or recess 27, which is formed in the slot 18 of the adjacent standard 5, and it will thus be seen that when said wedge is positioned therein the lever 19 will be incapable of downward movement, by 45 which the contact-pin 13 remains in fixed position, so as to be engaged by the pendulum 50 2 when the vessel assumes its normal position.

The operation of the herein-described regulating apparatus is as follows: The gun being aimed at a determined angle for firing and it is desired to discharge the same, a circuit is 55 closed through the electromagnets 23, whereby the contact-pin 13 is moved upwardly in the manner previously stated, thereby positioning the contact-point 16 in the transverse path of the point 10, and a circuit having been 60 closed through the gunner's switch it is obvious that immediately upon the point 10 engaging the point 16 the circuit will be completed therethrough, whereby the gun will 65 be discharged. It is to be noted, however, that the retaining-guide 6 confines the depending stem 7 within a limited radius. Hence although the pendulum 2 is capable of

universal movement such movement is not sufficient to permit the stem 7 swinging in such manner as to avoid the desired contact, 70 and it will be further observed that immediately upon engagement of the points 10 and 16 the gun will be discharged. This is a highly advantageous feature of the present invention inasmuch as the gun will be discharged 75 at the angle of aim previously determined, so that accuracy thereof is positively insured.

While the construction herein shown and described is believed to be a preferable embodiment of the invention, yet it is to be understood that the latter is susceptible of various changes in the form, proportion, and minor details of construction, and the right is therefore reserved to modify or vary the invention as falls within the spirit and scope 85 thereof.

Having thus described the invention, what is claimed as new, and desired to be secured by Letters Patent, is—

1. In an apparatus of the character described, the combination with a pendulum having a depending stem, of a spring-pressed contact-pin located beneath said stem and adapted to make contact therewith, substantially as described. 90

2. In an apparatus of the character described, the combination with a pendulum having a depending stem, of a spring-pressed contact-pin located beneath said stem and adapted to make contact therewith, and means 100 for withdrawing the contact-pin from the range of the stem, substantially as described.

3. In an apparatus of the character described, the combination with a pendulum having a depending stem, of a contact-pin located beneath said stem and adapted to make contact therewith, and a lever yieldably connected to the contact-pin, substantially as described. 105

4. In an apparatus of the character described, the combination with a pendulum having a depending stem, of a spring-pressed contact-pin located beneath said stem and adapted to make contact therewith, and means electrically controlled for withdrawing the contact-pin from the range of the stem, substantially as described. 110

5. In an apparatus of the character described, the combination with a pendulum having a depending stem, of a contact-pin located beneath said stem and adapted to make contact therewith, and an electrically-operated lever yieldably connected to the contact-pin, substantially as described. 115

6. In an apparatus of the character described, the combination with a pendulum having a depending stem, of a contact-pin located beneath said stem to make contact therewith, and a guide adapted to confine the movements of the pendulum to nearly a straight 120 line, substantially as described.

7. In an apparatus of the character described, a pendulum suitably suspended, a guide to limit the movements of the pendu-

- lum to nearly a straight line, and means located in the path of the pendulum to make electrical contact therewith, substantially as described.
5. In an apparatus of the character described, the combination with a pendulum having a depending stem, of a spring-pressed contact-pin located beneath said stem to make contact therewith, and a guide adapted to confine the movements of the pendulum to nearly a straight line, substantially as described.
9. In an apparatus of the character described, the combination with a pendulum having a depending stem, of a contact-pin located beneath said stem to make contact therewith, a guide for confining the movements of the pendulum to nearly a straight line, and means for withdrawing the contact-pin from 20 the range of the stem, substantially as described.
10. In an apparatus of the character described, the combination with a pendulum having a depending stem, of a contact-pin located beneath said stem to make contact therewith, means for confining the movements of the stem, and an insulating-sleeve on said stem, substantially as described.
11. In an apparatus of the character described, the combination with a pendulum having a depending stem, of a contact-pin located beneath said stem to make contact therewith, a guide for limiting the movements of the stem and an electrically-operated lever yieldably connected to the contact-pin, substantially as described.
12. In an apparatus of the character described, the combination of the pendulum having a depending stem, of a supporting-frame located beneath the pendulum, a spring-pressed contact-pin slidable therein and adapted to make contact with the stem, means for electrically operating said contact-pin to cause it to slide in the frame, substantially as described.
13. In an apparatus of the character described, the combination with a pendulum having a depending stem, of a frame located beneath the pendulum, a contact-pin slidable therein, an electrically-operated lever pivoted in the frame and yieldably connected to the pin, substantially as described.
14. In an apparatus of the character described, a pendulum suitably suspended, a guide to limit the movements of the pendulum to nearly a straight line, means located in the path of the pendulum to make electrical contact therewith, and means for insulating the pendulum from the guide, substantially as described.
15. In an apparatus of the character described, the combination with a pendulum having a depending stem, of a frame located beneath the pendulum, a contact-pin slidable therein, a lever pivoted to the frame and
- yieldably connected to the contact-pin, an adjustable wedge-shaped weight slidable on the lever and adapted to engage the frame to hold the contact-pin in a fixed position and means for operating the lever, substantially as described.
16. In an apparatus of the class described, the combination with a pendulum electrically connected with a gun, a depending stem carried by the pendulum, a contact-point holder carried by said stem, and a contact-point arranged in said holder, of a supporting-frame arranged beneath the pendulum, a contact-pin slidably mounted in said frame and adapted to close the circuit between the pendulum and the gun, a contact-point holder carried by said pin, a contact-point arranged within said holder and having its body elongated to provide a comparatively large surface for engagement by the contact-point of the pendulum, a lever fulcrumed in said supporting-frame and upon which the contact-pin is mounted, a spring carried by said lever and adapted to permit said pin having a yielding contact with the pendulum, a weight mounted upon said lever, a wedge arranged within said weight and adapted to engage the supporting-frame for retaining the contact-pin in fixed position with relation to the pendulum, an oblong guide supported on the frame and surrounding the depending stem for confining the movements thereof to nearly a straight line, and an insulating-sleeve around the stem to prevent electrical contact between the stem and the guide, substantially as described.
17. In an apparatus of the character described, the combination with a pendulum having a depending stem, of a means for confining the movements of the stem to nearly a straight line, and an elongated contact-pin located beneath the pendulum with its long edge across the path of the stem, substantially as described.
18. In an apparatus of the character described, the combination with a pendulum having a depending stem, of a means for confining the movements of the stem to nearly a straight line, an elongated contact-pin located beneath the pendulum with its long edge across the path of the stem, and means for withdrawing the contact-pin from the range of the stem, substantially as described.
19. In an apparatus of the character described, the combination with a pendulum having a depending stem, of a contact-pin located beneath the pendulum and a removable contact-point carried by said pin adapted to engage the depending stem, substantially as described.
